STOKER

Jesse L. Hinderer, Canton, Ohio

Application September 6, 1932, Serial No. 631,795

6 Claims. (Cl. 110—45)

The invention relates to stokers and more particularly to an underfeed stoker especially adapted for use in connection with a domestic furnace.

There are many objections to the types of underfeed stokers, for domestic furnaces particularly, which are at present in use. One objection is the manner in which the slack, powdered coal or other fuel feeds from the conveyer upward over the tuyère and grate of the furnace. Ordinarily the tuyère is of circular construction, the upper edge thereof being located in a horizontal plane and the coal is fed up through the same by means of an upwardly curved, flared chamber communicating with the end of the coal feed tube.

It has been found that with such a construction there is a tendency for the coal to bank or pile higher at the rear side of the combustion chamber of the furnace, thus making it impossible to maintain an even fire bed over the entire grate.

One object of the present improvement is to provide a construction of feed chamber and tuyère which will cause the coal to be fed evenly over the entire grate so as to produce an even firebed. This object may be attained by providing substantially a right angle in the front or upper side of the feed chamber and by providing an oval or elliptic tuyère with its major axis in a plane at right angles to the axis of the feed tube, the rear side of the tuyère being higher whereby the coal is fed upward through the feed chamber and evenly over the entire grate, producing a substantially even fire bed thereon.

While various devices have been provided for shaking the grates of stoker furnaces, both mechanically and manually, in order to sift ashes and other small particles of products of combustion through the grate into the ash pit, it is not known that there are any stoker furnaces in use provided with means for dumping the grates whereby clinkers and other large objects may be passed through the grates into the ash pit.

It is quite inconvenient and often difficult to manually remove clinkers and the like from the top of the grate and for this reason a further object of the improvement is to provide means for entirely dumping the grate of the improved stoker so as to empty the entire contents of the grate into the ash pit when desired. This object may be attained by providing a radial dumping grate with means for normally preventing complete dumping of the grate when the same is shaken to sift ashes therethrough.

Another objection to stoker furnaces such as

are now in use is the inconvenience and difficulty in removing ashes from the ash pit and in order to overcome the same, a further object of this improvement is to provide means for spraying the ashes with water or the like so that they may be easily removed without producing any unnecessary dust or dirt in the cellar or other place in which the furnace is located.

Another object of the improvement is to provide an air splitting device between the fan or other source of air under pressure and the furnace, with balanced dampers therein whereby the desired amount of air may be conveyed to the air chamber from which air is fed through the tuyère to the fire bed while the remainder of the air from the fan is passed into the heating jacket or chamber of the furnace so as to assist in the creation of a circulation of air from the heating jacket through the flues and registers of a hot air system.

A still further object of the improvement is to provide an air conditioning apparatus located in the air pressure line to the heating jacket whereby the air is moistened before it is passed through the flues to the registers.

Another object of the improvement is to provide a manually operated valve or damper for controlling the admission of air beneath the grates from the air chamber.

The above, together with other objects which will be hereinafter pointed out or which will be apparent from an inspection of the drawings and the following description, may be attained by constructing the improved stoker in the manner illustrated in the accompanying drawings, 90 in which

Figure 1 is a plan sectional view of a hot air furnace showing the improved stoker connected thereto;

Fig. 2, a side elevation of the same;

Fig. 3, a plan view of the grate and tuyère of the improved stoker;

Fig. 4, a side elevation of the same showing the grate rocking and dumping mechanism and the spraying device for the ash pit;

Fig. 5, a vertical sectional view of the mechanism shown in Fig. 4, taken as on the line 5—5, Fig. 3;

Fig. 6, a plan sectional view of the grate rocking and dumping mechanism;

Fig. 7, a detail sectional view of one grate bar and a portion of the grate rocking and dumping ring showing the parts in normal position, taken as on the line 7—7, Fig. 5;

Fig. 8, a similar view showing the grate bar in the dumped position;

Fig. 9, a detail perspective view of the locking and adjusting bar for the grate shaking and dumping mechanism;

Fig. 10, an end elevation of the air conditioning apparatus;

Fig. 11, a longitudinal sectional view through the same as on the line 11—11, Fig. 10;

Fig. 12, a vertical longitudinal sectional view through the air splitting mechanism for conveying a portion of the air from the fan to the heating jacket of the furnace;

Fig. 13, a plan sectional view of the same; and

Fig. 14, an end view of the air splitting mechanism.

Similar numerals refer to similar parts throughout the drawings.

The furnace illustrated may be of any usual and well known construction comprising the outer shell or heating jacket 15 and the inner shell or fire pot 16 spaced concentrically therefrom as in usual practice and forming the heating chamber 17 therebetween, the combustion chamber 18 being defined within the walls of the fire pot or inner jacket 16. The outer shell 15 may be provided with the usual firing door 19 communicating with the combustion chamber 18 and with the usual ash pit door 20 communicating with the ash pit 21, all as in usual and ordinary furnace practice.

The improved stoker mechanism to which the invention pertains includes a hopper 22 adapted to receive the fuel which may be slack, powdered coal or other finely divided fuel which is conveyed from the hopper to the furnace through the coal feed tube 23 communicating with the lower portion of the hopper and having mounted therein the coal feed screw 24 which carries the fuel therethrough.

This coal feed screw is driven by means of any suitable gearing located in the gear case 25 driven by means of a worm upon the shaft 26 which is provided with a pulley 27 connected as by the belt 28 to the pulley 29 upon the shaft 30 of the motor 31. A blower fan is mounted upon the shaft 26 and located within the fan casing 32.

The inner end of the coal feed tube 23 is received within the neck 33 of the forwardly and upwardly curved and flared coal feed chamber 34. It should be noted that the inner or upper side of this coal feed chamber is not curved concentric to the lower and outer side 35 thereof but forms substantially a right angle as shown at 36 in Fig. 5.

The upper end of the coal feed chamber is substantially circular and communicates with the lower substantially circular end 37 of the tuyère block 38. The central opening in the tuyère block 38 is substantially circular at its lower end as at 39 and is flared laterally at its upper end into a substantially elliptic or oval shape as indicated at 40, the major axis of said ellipse being in a plane at right angles to the axis of the feed tube 23 and the rear side of the tuyère block is higher than the forward side, as indicated at 41.

This oval shaped opening at the upper portion of the tuyère block with the rear side higher than the front, together with the angular inner and upper corner 36 of the feed chamber prevents the coal from banking or piling over the rear portion of the tuyère block and grates, and causes the coal to spread evenly around the tuyère block and grate, producing a uniform, even fire bed.

75 The coal feed chamber 34 and the air jacket

42 may be formed in a single casting as best shown in Fig. 5, so that the walls thereof together with the tuyère block 38 which rests upon the upper ends thereof, enclose an air chamber 43 which communicates with the blower fan as by the conduit 44. Upwardly and slightly inwardly angled passages 43a are formed through the tuyère block whereby air under pressure from the air chamber is directed into the fire bed.

The grate, which is of annular shape is preferably composed of a plurality of radial grate bars 45 mounted for rocking movement upon the radially disposed journals 46 mounted upon the upper ends of the brackets 47 which are fixed to the air jacket, at their lower ends, as by the screws or bolts 48, these brackets being curved outward and upward as at 49 and then inward and upward at their upper ends as at 50. The lower side of each of the grate bars 45 is provided with the radially disposed groove 51 which receives the journal 46, depending ears 52 being formed upon the grate bar at each side of said groove and pins or the like 53 being located through said ears for retaining the grate bar upon the journal.

For the purpose of shaking and dumping the grate, means is provided for rocking each of the grate bars upon its radial journal, this means being shown as a ring 54 surrounding the air jacket and spaced therefrom, said ring being rotatably mounted and operatively connected to the grate bars.

In order to rotatably mount this ring, the same may be provided at intervals with slots 55 through which are located rollers 56 mounted upon short radially disposed shafts 57 fixed to the air jacket 42 and provided at their outer ends with peripheral flanges 58 which prevent accidental dislodgment of the ring therefrom.

The inner end of each of the radial grate bars 45 is provided with a centrally located depending arm 59 having an outwardly disposed, substantially horizontal stud 60 fixed thereon and received in a notch 61 in the upper edge of the grate rocking and dumping ring 54. It will thus be seen that as this ring is rotated back and forth each of the grate bars will be radially rocked, as shown in Fig. 8, the degree to which the grate bars are moved being controlled by the amount of movement of the ring.

For the purpose of rotating the ring 54 backward and forward in order to shake or dump the grate bars, a curved link 62 is pivotally connected at its inner end, as at 63, to a depending stud 64 fixed to one side of the ring 54 as by the bracket 65 and screws or bolts 66, the outer end of this curved link having a socket 67 which receives one end of a pipe or tube 68 which is held in the socket as by a set screw 69.

This pipe or tube is slidably mounted through guides 70 supported upon the coal feed tube 23 or other suitable stationary portion of the apparatus and has a rod 71 fixed therein and extending substantially parallel to the coal feed tube, the other end of the rod being provided with a slotted or bifurcated member 72 within which is pivoted, as at 73, the lower end of the shaking and dumping lever 74 which is pivoted intermediate its ends, as at 75, upon a bracket 76 which may be fixed in any suitable manner adjacent to the lower end of the hopper 22. The upper end of the lever 74 is located between the angular ears 77 formed at opposite ends of the bracket 78 which may be fixed to the side of the hopper 22 adjacent to the upper end thereof.

A stop bar 79, which is illustrated in detail in

Fig. 9, is mounted for axial rotation between the ears 77 of the bracket 78 and arranged to normally hold the lever 74 against movement and to regulate the throw of the lever for shaking or 5 dumping the grate bars. This bar is provided at each end with an axial socket or opening 80 to receive the journal pins 81 and 82 which are journaled in the ears 77 of the bracket 78, the pin 82 being preferably provided with an angular end 10 portion 83 by means of which the bar 79 may be rotated upon its axis so as to provide for different adjustments of the shaking and dumping mechanism.

The bar 79 is provided on one face, near the center thereof, with the spaced pair of lugs 84 adapted to normally engage the lever 74, as shown in Fig. 1, to hold the same against movement. On another face the bar 79 is provided with the lugs 85, located near opposite ends of the bar. 20 When this face of the bar is turned toward the lever, the same may move between the lugs 85, giving a sufficient movement to rock the grate bars 45 only enough to shake the ashes from the fire bed into the ash pit.

25 By rotating the bar 79 to turn the unobstructed face 86 thereof toward the bracket 78, the lever 74 may be swung backward and forward along the entire length of the bar, being limited in its movement only by the lugs 77 upon the bracket, thus 30 permitting the grate bars to be rocked to the position shown in Fig. 8, permitting the entire fire bed to be dumped through the grate into the ash pit, thus providing for the passage of clinkers and the like through the grate.

35 The invention contemplates the admission of air from the air chamber to the underside of the grates in order to assist in combustion by forcing air under pressure upward through the fire bed and for this purpose a rotatable valve 87 40 may be located in the lower portion of the air jacket above the bottom plate 88 thereof, and provided with radial slots or openings 89 adapted to cooperate with similar slots or openings 90 in the plate 88 in order to control the amount 45 of air admitted to the underside of the grates, as well as to entirely cut off the same if desired.

Manually controlled means may be provided 50 for regulating the position of the damper or valve 87 and as shown, this may comprise a lever 91 fixed as by a pin 92 upon the depending end of the valve or damper shaft 93 which is journaled in the bearing 94 formed at the central portion of the plate 88. A link 95 may be pivotally connected to the end portion of the lever 91 55 and extended to a point where it may be conveniently operated through the ash pit door of the furnace, as shown in Fig. 2.

Means is preferably provided for dampening 60 the ashes in the ash pit so that they may be removed without creating an undue amount of dust and dirt in the cellar and this means may be in the form of an annular water jacket 96 located at the lower end of the air jacket 42 and surrounding the manually controlled valve or damper 65 for admitting air from the air chamber beneath the grate. This annular water jacket may be connected to a water supply pipe 97 and is provided on its underside with a plurality of small apertures 98 adapted to direct small streams or 70 jets of water over the ashes in the ash pit.

For the purpose of admitting air under pressure from the blower fan to the heating jacket of the furnace in order to assist in the creation of a circulation of air through the flues and 75 registers connected with the heating jacket, an

air splitting device is located in the casing 99 which communicates with the outlet side of the fan casing 32. The air conduit 44 leads from said air splitting device to the air jacket 42 and a somewhat similar conduit 100 leads from said air splitting device into the lower portion of the heating chamber 17, the inner end of said conduit being cut off at an angle, as indicated at 101 in Fig. 1, so as to direct the air upward through the heating chamber.

The casing 99 is divided into two substantially equal compartments 102 and 103 by means of the longitudinal partition wall 104, both of said compartments communicating at one end with the outlet side of the fan casing 32, while the compartment 102 communicates only with the conduit 44 and the compartment 103 with the conduit 100.

Balanced dampers 105 and 106 are located in the compartments 102 and 103 respectively, controlling the passage of air therethrough to the conduits. These dampers are both of the same construction, each being suspended from a shaft 107 connected to its upper end and journaled in the upper portion of the casing 99.

A hub 108 is fixed upon the outer end of each shaft 107 and has a rod 109 located diametrically therethrough, each end of the rod being threaded as at 110, a counterweight 111 being mounted upon each threaded end of the rod and held in adjusted position as by the lock nuts 112.

An arm 113 is fixed upon each hub, preferably at right angles to the rod 109 thereon, and is adapted to move across the face of the sector 114 provided with a plurality of apertures 115 for 110 selective engagement by the pins 116 and 117 which are arranged to be engaged by the arm 113 to limit the opening and closing limits respectively of the damper.

With this construction the damper 105 will be 115 automatically adjusted by the velocity of the air passing therethrough in accordance with the condition of the fire bed and this will permit any surplus of air from the fan, not used for combustion purposes, to pass through the other compartment 103 to the heating jacket of the furnace.

For the purpose of moistening the air in the hot air system, an air conditioning device may be provided in the casing 118 which communicates 125 with the inlet side of the fan chamber 32. The casing 118 may be provided with a removable cover 119 having a knob 120 for operating the same and the lower portion thereof is adapted to contain water indicated at W in Fig. 11, an outwardly inclined trough 121 communicating with the lower portion of the casing for the purpose of supplying water thereto.

A drain opening 122 may be provided in the bottom of the casing, normally closed as by the 135 stopper 123. A circular opening 124 is provided in each end of the casing 118 and a shaft 125 is journaled axially through the casing concentric with said openings and has a propeller wheel 126, fixed upon each end thereof, a perforate or porous 140 cylinder 127 being fixed at its ends to said propeller wheels and arranged to dip into the water in the bottom of the casing. The outlet 128 from the casing is located at right angles to the axis of the cylinder 127 and communicates with the 145 inlet to the fan chamber 32.

It will thus be seen that all of the air drawn into the fan casing passes through the openings 124 of the casing 118, rotating the propeller wheels 126, and with them the perforate cylinder 150

127 which is continually moistened by contact with the water in the bottom of the casing. The air then passes through the moistened perforate cylinder to the fan and is delivered therefrom 5 to the furnace.

I claim:

1. A stoker furnace including a coal feed tube, an upwardly curved feed chamber communicating with the feed tube, and a tuyère block communicating with the upper end of the feed chamber, the upper portion of the inner surface of said tuyère block being in the form of an ellipse with its major axis at right angles to the axis of the feed tube.
- 15 2. A stoker furnace including a coal feed tube, an upwardly curved feed chamber communicating with the feed tube, and a tuyère block communicating with the upper end of the feed chamber, the upper portion of the inner surface of said tuyère block being in the form of an ellipse with its major axis at right angles to the axis of the feed tube, and being higher on the side opposite to the feed tube than at any other point.
- 20 3. A stoker furnace including a coal feed tube, an upwardly curved feed chamber communicating with the feed tube, the upper corner of said feed chamber adjacent to said feed tube being substantially a right angle, and a tuyère block communicating with the upper end of said feed chamber, the upper portion of the inner surface of said tuyère block being in the form of an ellipse with its major axis at right angles to the axis of the feed tube.
- 25 4. A stoker furnace including a coal feed tube,

an upwardly curved feed chamber communicating with the feed tube, the upper corner of said feed chamber adjacent to said feed tube being substantially a right angle, and a tuyère block communicating with the upper end of the feed chamber, the upper portion of the inner surface of said tuyère block being in the form of an ellipse with its major axis at right angles to the axis of the feed tube and being higher on the side opposite to the feed tube than at any other point.

5. A stoker furnace including an annular tuyère, means for feeding coal upward through the tuyère, an annular grate surrounding the tuyère and comprising a plurality of radial grate bars, means for rocking each grate bar upon an axis radial to the grate, a lever for operating said grate rocking means and an axially rotatable stop bar having a plurality of faces and differentially spaced lugs on various faces for limiting the movement of said grate rocking lever.

6. A stoker furnace including an annular tuyère, means for feeding coal upward through the tuyère, an annular grate surrounding said tuyère and comprising a plurality of radially journaled grate bars, a ring rotatably mounted beneath the tuyère, a depending arm upon each grate bar pivotally connected to said ring, an operating lever operatively connected to said ring for rotating the ring, and an axially rotatable stop bar having a plurality of faces and differentially spaced lugs on various faces for limiting the movement of said operating lever.

JESSE L. HINDERER.
